UNITED STATES PATENT OFFICE.

ISAAC W. HENDERSON, OF CHICAGO, ILLINOIS, ASSIGNOR TO THE WESTERN PUBLISHING HOUSE, OF SAME PLACE.

MAP CASE AND HOLDER.

SPECIFICATION forming part of Letters Patent No. 414,945, dated November 12, 1889.

Application filed March 25, 1889. Serial No. 304,737. (No model.)

To all whom it may concern:

Be it known that I, ISAAC W. HENDERSON, residing at Chicago, in the county of Cook and State of Illinois, and a citizen of the United States, have invented certain new and useful Improvements in Map Cases and Holders, of which the following is a specification, reference being had to the accompanying drawings, in which—

- 10 Figure 1 is a perspective showing one map exposed. Fig. 2 is a section at line 2 of Fig. 3. Fig. 3 is an end view looking toward the right of Fig. 2, the maps being removed. Fig. 4 is a cross-section looking to the left, the 15 circular case which carries the maps being closed. Fig. 5 is a similar section, the case which carries the maps being open and all of the maps being removed. Fig. 6 is a detail, being an elevation showing one of the 20 maps removed from the case and a device connected with the map for the purpose of hanging the same against a wall. Fig. 7 is a vertical section taken at the right hand of the maps and case. Figs. 8 and 9 show a 25 modification in which the maps are not designed to be removed from the case for the purpose of being hung against a wall. Fig. 10 is a detail showing a device for hanging up a single map when detached from the 30 case.

The leading objects of my invention are to provide an improved map-case capable of receiving and holding a number of maps, which case can be readily closed when the maps are 35 not on exhibition and readily opened for the purpose of exhibition; also, to provide improved devices for supporting the several maps in the case; also, to provide devices by means of which the maps can be easily removed from the case; also, to provide each 40 map with an attachment which does not interfere with its use in the case, and which facilitates the hanging of the same against a wall when removed from the case, all of which 45 I accomplish as illustrated in the drawings and hereinafter fully described.

That which I claim as new will be pointed out in the claims.

In the drawings, A represents a rectangular 50 case, which is open on one side. This case

consists of pieces of wood a b, which form the top and bottom and a portion of the back, with end pieces and a thin back piece c.

d are triangular strengthening-pieces, to which the strips a b are secured.

Within the case A there is secured a circular case B, which consists of two round end pieces C C and a thin piece of veneer or paper-board E, secured to such end pieces, but extending only a little more than half-way around the same, leaving an open space v the remainder of the distance.

e f are metal bands, one on each of the pieces C D.

F is a piece of wood which, as shown, is 65 eight-sided. On one end of this piece there is secured a head G, which may be of spun metal, which, as shown, is provided near the center with a recess to receive the end of the shaft or strip F, which at this point is round, 70 and the head G is secured to the strip or shaft F by means of two or more screws g. The head G is provided on its inside with a number of studs h, corresponding in number with the number of maps which the case is 75 adapted to receive. At the other end of the piece F there is another head H, which is secured upon the strip F by means of screws i.

j are a number of springs secured at one end to the head H, the other end of each 80 spring being free. To each of these springs there is secured a stud k, and each of these studs k passes through a hole in the head H.

I are a number of spring-rollers such as are in common use for curtains and maps. 85

l are pieces of metal, one end of each of which is provided with a hole of the proper form to receive one of the journals or one of the rectangular irons at the ends of the rollers I.

J are strips of wood, one for each map or roller, and each strip is secured to the pieces of metal l, which receive one of the rollers.

m are pieces of metal, two of which are pivotally connected to each one of the strips J, 95 so that these pieces m can be turned around out of the way, as shown in Fig. 6, or can be turned up, as shown in Fig. 10. Each piece m is provided with a hole n.

o are strips of metal secured to the inside 100

of the case A, and they project forward a little outside of the case. These projecting ends are provided with holes to receive the screws K, which pass through the heads C D into the shaft or piece F, by means of which the heads C D are pivoted to the case A, so that these heads and the parts connected therewith can be rotated. The shaft F and the heads G H thereon are also pivotally connected upon the screws K, so that such shaft and heads can be rotated independently of the secondary case.

p is a strip secured to one edge of the part E, which strip forms a stop to limit the movement of the secondary case in both directions, the stop coming in contact with one edge of the case A.

The case A is to be provided with eyes or other suitable devices by means of which this case can be hung upon hooks upon a wall, or it can be permanently secured to the wall in any suitable manner, if desired.

The heads C D and the strip or piece E secured to such heads together form a secondary case open on one side, in which the maps are located, and this secondary case rotates in the case A.

The parts can be put together as follows: The heads G H are to be secured to the ends of the shaft or strip F. A secondary case B is to be placed within the case A, and the heads G H, with the strip F, are to be placed within the secondary case, and such secondary case, with the heads G H and strip F, are to be secured pivotally to the case A by means of screws K, which pass through the strips o, through the heads or pieces CD, and into the strip F, as shown in the drawings.

The several maps upon the rollers, together with the pieces of wood J, the same having been arranged and put together, as shown in Fig. 6, can then be placed one by one in the heads G H, one of the pieces l being placed upon one of the pins h on the head G, as shown in Fig. 7. The proper spring j being then thrown back by hand, the metal piece l at the other end of the roller can be brought into proper position to allow the proper pin k, carried by such springs j, to enter in such piece of metal l, when the spring is released, as shown in Fig. 2. The maps all being in place, the secondary case can be rotated by hand, bringing it into the position shown in Fig. 4, when all the maps will be within the two cases A B, and the maps will be thoroughly protected, the open space in the case B being at this time within the case A.

When it is desired to exhibit any one of the maps, the secondary case is to be partially rotated, bringing it into the position shown in Fig. 5, when the open space therein will be exposed. The maps are all supposed to be properly numbered or otherwise designated, and all the maps can be rotated together in the secondary case without changing the position of such case, because the shaft F, which carries the heads G H, which carry all the

maps, is pivoted by means of the screws K in the heads C D, so that by rotating the maps within the secondary case any one can be brought to the front and drawn down and exhibited.

It is frequently desirable, especially in schools where two or more rooms are used, to remove a single map from this case and take it to another room for exhibition. This I have made provision for, and either one of the maps can be removed from the secondary case simply by withdrawing the proper spring j until the stud or pin k is released from the metal strip connected with the map, and then the map, with the strip of wood J, can be withdrawn from the case, and by means of the devices m can be hung upon a wall wherever desired.

In Figs. 8 and 9 I have shown a modification in which no provision is represented for removing either one of the maps from the case, and hence the strips of wood J and pieces of metal l are omitted, as well as the springs j. With this modification two heads to receive the maps may be used, one of which L is shown in Fig. 9, and the other head L' (shown in Fig. 8) is similar in construction, except that the holes therein may be round instead of triangular. These two heads take the place of the two heads G H, and the maps are supported in these heads and can be placed in position by securing one of the heads to the shaft F and inserting the journals at one end of the map in such head, then bringing the other head to its proper place and securing the same to the shaft F, after which the shaft and maps can be placed in the secondary case, as before described. With this construction I secure all of the advantages gained by the construction shown in the other figures, except that the maps cannot be removed, and this modification is designed for use in places where it is not expected that either one of the maps will be removed from this case. In this modification there will be a case A, a secondary case B, rotating within the case A, a rotating shaft, and heads carrying maps and located within the secondary case, as before described, the maps being supported directly in the two heads L L' instead of in the strips l.

The screws K are pivoted both in the irons o, secured to the case A, and also in the heads C D, so that these heads and the shaft F can rotate together; or the secondary case, of which the heads C D form a part, can be prevented from rotating, and the shaft F, with the parts connected therewith, can be rotated in the secondary case. The free end of each may is connected with a strip of wood r, as usual.

What I claim as new, and desire to secure by Letters Patent, is as follows:

1. The combination of a case A, open on one side, a secondary case B, also open on one side, a shaft F, provided with a head on each end adapted to receive a series of map-rollers,

the shaft F being pivotally connected with the case A and also with the secondary case B, whereby the shaft F and parts secured thereto can be rotated either with or independently of the secondary case, substantially as and for the purpose specified.

2. In a map case and holder, the combination of a rotating shaft F, a head H upon one end of said shaft, such head being provided with a series of springs, each carrying a stud, and a second head G on the other end of the shaft, and provided with means thereon for supporting map-rollers, substantially as and for the purposes specified.

3. A series of map-rollers I, strips l, and strips of wood J, in combination with a shaft F, provided with heads G H, one of such heads having springs j, carrying studs k, and the other head being provided with means thereon for supporting map-rollers, substantially as and for the purposes specified.

ISAAC W. HENDERSON.
